VALVE MECHANISM FOR GAS-ENGINES.

1,309,906.

Specification of Letters Patent. Patented July 15, 1919.

Application filed November 18, 1915. Serial No. 62,092.

To all whom it may concern:

Be it known that I, FRANK L. MORSE, a citizen of the United States, residing at Ithaca, in the county of Tompkins and State of New York, have invented a certain new and useful Improvement in Valve Mechanism for Gas-Engines, of which improvement the following is a specification.

This invention relates to valve mechanism for internal combustion engines, and more particularly to valves of the rotary type, the principal object being to provide means for increasing the volume flow of gas through a port of the valve at each open period, for a given size of ports and rate of operation.

This feature of my improvement comprises a valve operating mechanism adapted to rotate the valve at a variable speed through each revolution, preferably by accelerating the opening movement and retarding the closing movement, whereby the port remains open for a longer period at each instance than when driven at a uniform speed. This feature may be applied to either the admission or to the exhaust, but preferably to both.

Another feature of my invention comprises improved means for maintaining a fluid tight joint bearing between the inlet and discharge ports, and between the ports of adjacent cylinders.

In the operation of rotary cylindrical valves of this character, it has been found that, due to the difficulty of providing efficient cooling means, the valve runs at a much higher temperature than the casing, and there is a marked difference between the amount of expansion of the valve casing and of the valve, which results in an excessively tight fitting valve at high temperature, or a wasteful leakage around the valve when the parts are at comparatively low temperature, as when starting the engine. Another feature of my improvement, therefore, comprises a rotary valve formed of a metal having a lower co-efficient of expansion than the valve casing whereby the same may be made to fit closely in its chamber within the casing when the parts are cold, and expand at about the same rate as the casing as the temperature of the parts rise, due to the operation of the engine, the temperature of the valve being then greater than that of the casing.

In the accompanying drawings: Figure 1 is a vertical longitudinal section of a gas en-

gine showing one form of valve mechanism embodying my improvement; Fig. 2, a transverse section taken on the line 2—2 of Fig. 1; Fig. 3, a fragmentary view taken in transverse section in another plane and showing one form of device for setting up the packing and sealing strips; Fig. 4, a transverse section taken on the line 3—3 of Fig. 1, with certain parts of the flange plates broken away to more fully show all parts of the mechanism; Fig. 5, a detail view in perspective showing the internal gear connection; Fig. 6, a view similar to Fig. 4, but showing a modified form of valve operating mechanism; Fig. 7, a sectional view taken on the line 7—7 of Fig. 6; Fig. 8, a horizontal sectional view of the mechanism shown in Fig. 6; and Fig. 9, a fragmentary view, in transverse section, showing a modified form of means for setting up the sealing strips.

According to the construction shown in the drawings, the engine comprises a frame or casing, 10, containing one, two, or more cylinders, 11, having pistons, 12, the upper portion of the casing being formed with a cylindrical chamber containing the rotary cylindrical valve, 13, located over the tops of the cylinders, and having through ports, 14, adapted to establish communication from the gas supply, 15, and inlet port, 16, to the cylinder, and from the cylinder to the exhaust port, 17, in certain positions during the revolution of the valve.

In order that the valve may be operated at high speed and yet have the port open a sufficient length of time, I provide an intermediate driving mechanism between the engine shaft and the valve, which operates to turn the valve more slowly during certain parts of its revolution at such times as the ports may be open, than during other portions of the revolution, and for this purpose, I have shown a rotatable element such as a sprocket gear driven from the engine shaft and having a variable speed driving connection with the valve. One form of such mechanism is shown in Figs. 1 and 4, and comprises a sprocket gear wheel constructed in two parts, the outer or peripheral portion, 20, carrying the sprocket teeth, and adapted to be driven directly by the sprocket chain from the engine shaft, and the inner or hub portion, 21, keyed upon the stem of the valve and mounted to have a limited amount of rotary movement relative to the outer portion. A section of the web portion of the

two parts of the sprocket is cut away to provide space for the connecting means, and for guiding the outer portion on the hub portion, a pair of segmental plates, 22, are set 5 cured, one upon each side of the web of the hub portion and overlapping the web of the outer portion, while another pair of segmental plates, 23, are fastened, one on each side of the peripheral portion of the sprocket 10 and overlapping the web of the hub portion, there being sufficient clearance between the ends of the respective pairs of plates to allow for the relative rotary or oscillatory movement between the parts of the sprocket. 15 On one part of the sprocket, as in the plates, 23, is mounted a shaft, 24, carrying a small spur gear or pinion, 25, fixed thereon and having a crank, 26 between the plates, 23, pivotally connected by the rod, 27, with 20 the other portion of the sprocket, as shown, the rod being pivotally connected to the plates, 22. The rod may be adjustable, if desired. The pinion, 25, meshes with an internal circular rack, 28, fixed to the casing or 25 frame.

The ratio between the internal rack and the pinion may be made to suit the form of valve as to the number of ports and number 30 of cylinders, that shown in the drawings being four to one, that is, the rack having four times as many teeth as the pinion. With this construction, it will be seen that during each revolution of the sprocket, the pinion will necessarily revolve four times, making 35 four complete revolutions of the crank, 26. This operates through the rod connection to give a variable speed to the hub portion of the sprocket, and consequently to the valve throughout each revolution thereof. When 40 the connecting rod is moving in one direction, with reference to the crank, the rotary movement of the hub portion is being retarded relative to the peripheral portion, and when the connecting rod moves in the 45 opposite direction, the rotary movement of the hub portion is accelerated relative to that of the periphery. With the four to one ratio, as shown, the periods of the accelerated and retarded movements will each be 50 one-eighth of a complete revolution of the sprocket and the valve, and the preferred arrangement is such that the movement of the valve is accelerated when the port is opening and then retarded as the port is closing. By 55 this means communication through the port is maintained for a longer period of time at each opening and closing of the same, and the volume flow of gas either from the inlet or to the exhaust is thereby increased. 60 In Figs. 6, 7 and 8 of the drawings, there is shown a modified form of mechanism for effecting the alternate successive retarded and accelerated movements of the hub portion of the sprocket, and comprising, in lieu of the 65 crank shaft, pinion and rack, a bent lever

pivotaly mounted at 24^a, in the plates, 23, and having one arm, 26^a, coupled by connecting rod, 27^a, with the plates, 22, and the other arm, 25^a, provided with a roller, 25^b, bearing against the inner surface of the cam 70 ring, 28, fixed upon the casing. In this construction the inner surface of the cam ring is formed with the desired number of rises and depressions properly located to produce the required oscillatory movement of the bent 75 lever during the revolution of the sprocket, and consequently cause the alternate successive retarded and accelerated movements of the sprocket hub and valve, as above described. 80

According to another feature of my invention, I provide improved means for preventing leakage and escape of gases from the inlet port and cylinder to the exhaust port, said means comprising a sealing or packing 85 strip, 30, located in a suitable recess in the casing, longitudinally of the valve, and between the inlet port, 16, and exhaust port, 17. The valve is provided with suitable packing rings, 34, on both sides of the port, 90 14, for each cylinder, and the sealing strip, which is arranged longitudinally and bears upon the valve, is of sufficient length to lap over the packing rings, there being a separate sealing strip for each cylinder, and having a spring actuated means, such as rod, 31, spring, 32, and screw plug, 33, shown in Fig. 3, for pressing the sealing strip against the valve and one side of its chamber, for maintaining a fluid tight joint. 100

There are preferably two of the spring actuated rods, 31, for each strip, the same being located near the ends, and as each of the strips extends beyond the packing rings for its respective cylinder, it will be seen 105 that an effectual packing is provided against the escape of gas from the inlet port to the exhaust port. The sealing strip may be provided with longitudinal packing grooves on the side engaging the wall of the chamber 110 against which it is pressed by the spring. 115

Fig. 9 shows a modified spring device in which the spring, 32^a, acts on a wedge piece, 31^a, engaging the sealing strip, 30^a, and pressing the same against the valve and the 120 wall of the chamber.

According to another feature of my improvement, I construct the valve, 13, of nickel-steel, or some other metal composition which has a lower co-efficient of expansion than the ordinary cast iron or other metal casing in which it is mounted. In this way a comparatively close fit may be maintained between the valve and casing at the varying temperatures. When the engine is running, and the parts are heated up to their usual high temperatures, the valve 125 will be at a higher degree of temperature than its inclosing casing, due to the more effectual cooling of the latter by the circ 130

lating water, but as the co-efficient of expansion of the valve is less than that of the casing, the total amount of expansion resulting from their respective temperatures 5 will be substantially the same, and consequently the valve will be neither so loose as to permit leakage around it when the engine is first started and the parts are cold, nor too tight to operate smoothly and efficiently 10 when the parts are heated up to their maximum temperatures.

It will now be seen that, by means of my improvement, the movement of the valve during each revolution will be a series of 15 alternate accelerations and retardations, and the mechanism is preferably so timed that the latter portion of an acceleration shall occur during the opening movement of the port, and the succeeding retardation 20 shall occur during the closing movement of the port, thereby maintaining communication through said port open for a much longer period than would otherwise be the case, and consequently greatly increasing the 25 volume flow of gas therethrough.

The timing of the respective movements and the number of accelerations and retardations per revolution may be made to suit any given conditions as to number of cylinders, location of ports, etc., by simply changing the proportion of the parts, size of gears, or location of cams, and thereby adapt my improvement to the various different styles and arrangement of engines.

30 Another advantage derived from this feature of my improvement is that a smaller size of valve may be employed for accomplishing the same work, thereby effecting a saving in weight and cost and also greatly 40 reducing the amount of gas wasted by means of the use of the smaller sized port in the valve.

Having now described my invention, what I claim as new and desire to secure by Letters Patent is:

1. In an engine, the combination with a rotary valve having ports, of a rotatable element driven by the engine at a substantially uniform rate, and an intermediate 50 variable speed mechanism so connected as to gradually accelerate the movement of the valve during the opening of the port and to gradually retard said movement during the closing of said port.

2. In an engine, the combination with a rotary valve, of a rotatable gear formed in two parts, comprising an outer portion driven from the engine and an inner or hub portion connected to said valve, and an intermediate variable speed driving connection 60 between the two portions of the gear.

3. In an engine, the combination with a rotary valve, of a rotatable gear formed in two parts, comprising an outer portion driven from the engine and an inner or hub 65 portion connected to said valve, an element pivotally mounted on one portion and having a rod connecting the same with the other portion of the gear, and means operated by the rotation of the gear for moving said element to reciprocate the connecting rod.

4. In an engine, the combination with a rotary valve, of a rotatable gear formed in two parts, comprising an outer portion driven from the engine and an inner or hub 75 portion connected to said valve, an arm pivotally mounted on one portion of the gear, a rod connecting the arm with the other portion of said gear, and means for swinging said arm during the rotation of 80 the gear.

5. In an engine, the combination with a rotary valve, of a rotatable gear formed in two parts, comprising an outer portion driven from the engine and an inner or hub 85 portion connected to said valve, and a cam operated mechanism for producing a relative oscillatory movement between the parts of the gear during its revolution.

6. In an engine, the combination with a rotary valve, of a rotatable gear formed in two parts, comprising an outer portion driven from the engine and an inner or hub portion connected to said valve, an element pivotally mounted on one portion and having a rod connecting the same with the other portion of the gear, and a cam device for oscillating said element during the revolution of the gear.

7. In an engine, the combination of a valve casing having inlet and exhaust ports, a rotary cylindrical valve mounted therein and having a port for coöperating therewith, a sealing strip mounted in a recess in said casing between said inlet and exhaust ports 105 and extending longitudinally of the valve, and a spring for forcing said strip against the valve and one side of said recess.

8. In an engine, the combination of a valve casing having inlet and exhaust ports, a rotary cylindrical valve mounted therein and having a port for coöperating therewith, a sealing strip mounted in a recess in said casing between said inlet and exhaust ports and extending longitudinally of the valve, and a 110 spring actuated plunger for pressing said strip against the valve and against one side of said recess.

In testimony whereof I have hereunto set my hand.

FRANK L. MORSE.
